UNITED STATES PATENT OFFICE.

ELIZABETH M. PORTER, OF GREENE, NEW YORK.

OVEN-MAT.

1,126,270.

Specification of Letters Patent.

Patented Jan. 26, 1915.

Application filed March 5, 1913. Serial No. 752,044.

To all whom it may concern:

Be it known that I, ELIZABETH M. PORTER, a citizen of the United States, residing at Greene, in the county of Chenango and State 5 of New York, have invented certain new and useful Improvements in Oven-Mats, of which the following is a specification.

My invention relates to an improvement in oven mats in which a mat formed with a 10 non-conducting surface is provided to be used in ovens or other heated places, for the purpose of protecting bake stuffs from being burned during the process of baking, and it has for an object to provide a light, adjustable mat having a surface composed of non-conducting material, rigidly supported by a frame or other back, and to be easily manufactured and easily adapted to different kinds of ovens.

20 With this object in view my invention consists in certain novel features of construction and arrangement of parts as will be hereinafter fully described and pointed out in the claim, reference being had to the 25 accompanying drawings, in which—

Figure 1 is a side elevation of my device as applied to bake stuffs in an oven. Fig. 2 is a top plan view of my device. Fig. 3 is a sectional view of my device taken on 30 line 3. 3 of Fig. 2. Fig. 4 is a top plan view of my device in which the top is perforated. Fig. 5 is a sectional view of my device with perforated top taken on line 5. 5 of Fig. 4. Fig. 6 is a longitudinal section of a modified 35 form of my device taken on the line 6. 6 of Fig. 7, and Fig. 7 is a cross section taken on the line 7. 7 of Fig. 6.

In carrying out my invention, I provide a top surface, A comprised of metal, having 40 overlapping edges, B, B. Beneath the top A and fastened to it by the overlapping edges B, B I have a layer of asbestos paper or other non-conducting material C. Mounted in each end of the top A, I have the 45 rings d, d. These rings permit ready manipulation of the mat and also afford means whereby the mat may be suspended from the oven shelf, if desired. The top A may be perforated forming an open frame 50 work A' with the cross bars A^x as shown in Fig. 4, and mounted on the lower side of

the same I have a layer of asbestos C, or other non-conducting material.

In a modified form of my device I have the top support surface, A formed in two 55 parts, A', A², part A' sliding over the part A². Part A² has projecting from it the bent guides x, x, which are bent over the ends of the part A' to permit the part A' to slide relative to the part A² and prevent separation of the parts. Part A' has projecting from its upper surface at the inner end, the lugs y, y, contacting with the bent lugs, x, x when the part A' is pulled out from over the part A², thus limiting the extension 65 of the parts. By these means the part A' is held in a slideable position over part A², and the entire body A can be varied in length by sliding the parts, one over the other, and is thus better adapted to different 70 sized ovens and for different purposes.

In operation I place the mat with the non-heat conducting surface, downward upon the bake stuff in the oven. It prevents the materials from becoming burned or 75 blackened by the excessive heat at the top while being baked within their respective receptacles, and thus enables the entire article to be baked evenly throughout.

Having thus described my invention, what 80 I claim as new and for which I desire Letters Patent is as follows:

An extensible oven mat comprising upper and lower parts, each formed of a non-conducting sheet and a metallic frame disposed above said sheet, with the end and side edges of the frame bent to over-lap the non-conducting sheet to hold the sheet and frame together, guide lugs carried by the lower part and bent to over-lap the upper 85 part but permitting a sliding movement between the parts, and stop lugs carried by the upper part for co-operating with the guide lugs to limit the extension of the 90 parts.

95 In testimony whereof I have affixed my signature in presence of two witnesses.

ELIZABETH M. PORTER.
